UNITED STATES PATENT OFFICE

CHARLES W. FLOOD, JR., OF PHILADELPHIA, PENNSYLVANIA, ASSIGNOR TO VOIGT COMPANY, OF PHILADELPHIA, PENNSYLVANIA, A CORPORATION OF PENNSYLVANIA

DESIGN FOR A LIGHTING FIXTURE

Application filed August 28, 1929. Serial No. 32,585. Term of patent 7 years.

To all whom it may concern:

Be it known that I, CHARLES W. FLOOD, JR., a citizen of the United States, residing at Philadelphia, in the county of Philadelphia, and State of Pennsylvania, have invented a new, original, and ornamental Design for a Lighting Fixture, of which the following is a specification, reference being had to the accompanying drawing, forming part thereof.

Figure 1 is a side elevation of a lighting fixture showing my new design; and Figure 2 is a horizontal sectional view as on line 2—2 Figure 1.

I claim:

The ornamental design for a lighting fixture, as shown.
